UNITED STATES PATENT OFFICE.

EDWARD POSSON, OF CHICAGO, ILLINOIS.

COMPOUND HAND-BRAKE MECHANISM.

1,399,076.

Specification of Letters Patent.

Patented Dec. 6, 1921.

Application filed January 20, 1919. Serial No. 272,219.

To all whom it may concern:

Be it known that I, EDWARD POSSON, a citizen of the United States, residing at Chicago, in the county of Cook and State of Illinois, have invented certain new and useful Improvements in Compound Hand-Brake Mechanism, of which the following is a specification.

This invention relates to a compound hand-brake mechanism, and the present invention is an improvement on the apparatus described and claimed in my copending application, Serial No. 263,999, filed November 25, 1918.

15 The object of the invention is to provide a brake mast or shaft formed in complementary parts which are connected by transmitting mechanism adapted to increase the power applied to the brakes. For this purpose the brake mast is formed in two parts which are connected by gear mechanism located in a housing carried by the end sill of the car. The upper part of the brake mast is manually operated by the brakeman, and 20 the lower part of the mast which is connected to the brake chains moves at a lesser speed than the upper part, but the force applied thereto is multiplied by the intermediate gearing mechanism. Other objects 25 relate to various features of construction and arrangement which are pointed out more fully hereinafter.

The nature of the invention will be understood from the following specification taken with the accompanying drawings in which one embodiment is illustrated.

In the drawings—

Figure 1 shows an end elevation of a portion of a railway car with my improved brake mechanism applied thereto;

Fig. 2 shows an enlarged top plan view of the brake mechanism;

Fig. 3 shows a vertical section on the line 3—3 of Fig. 2;

Fig. 4 shows a vertical section on the line 4—4 of Fig. 2;

Fig. 5 shows a horizontal section on the line 5—5 of Fig. 3; and

Fig. 6 shows a horizontal section on the line 6—6 of Fig. 3.

In the drawing, the end sill 10 of the car is shown as comprising a channel beam 10^a connected to upper and lower plates 10^b and 10^c. A buffer plate 11 is secured to the end sill 10 at the middle part thereof, and this buffer plate carries a draw-bar carrier 12

secured thereto by bolts 13. These features do not form a part of the present invention, but are shown and described for the purpose of illustrating the adaptation of the 60 hand-brake mechanism.

The hand-brake mechanism is supported primarily by a plate 14 which rests upon and is bolted to the end sill 10. This plate supports a housing 15 which contains the 65 intermediate gearing mechanism, and which is provided with apertured lugs 16 engaged by bolts 17 which secure the housing to the supporting plate. The housing 15 is provided with an upwardly extending hood or 70 casing 15^a, carrying at its upper part a hub 18 which forms a bearing for the lower cylindrical portion of the upper part 20^a of the brake mast 20. The hand-wheel 21 is secured to the upper end of the brake mast, 75 as shown in Fig. 1, to permit the operation thereof by the brakeman. The upper part 20^a of the brake mast is surrounded by the collar 22 within the portion 15^a of the housing, and this collar is secured thereto by a 80 bolt 23, so that the withdrawal of the brake mast from the housing is prevented. The upper part of the brake mast is provided beneath the collar 22 with a part 24 of rectangular cross-section which forms a driv- 85 ing engagement with a compound gear member 25 having at the upper part thereof a ratchet wheel 26, the teeth of which are engaged by a pawl 27 pivoted on a bolt 28 extending downwardly through the casing 90 15 and through the plate 14. The lower part of the gear member 25 is provided with a pinion 29 which meshes with the teeth of a gear 30 located in the lateral extension 15^b of the housing and pivoted on a bearing pin 95 31 which extends through apertures in the upper and lower walls of the housing and is secured in position by a transverse pin 32 extending through the boss 33 formed on the upper wall of the housing. A pinion 35 100 located below and formed integrally with the gear 30 is adapted to mesh with a gear 36, by which the lower portion 20^b of the brake mast is driven. The gear 36 is provided with an integral downwardly extend- 105 ing hub or sleeve 36^a which receives the upper extremity of the lower portion of the brake mast and is secured thereto by a pin 37. A cylindrical aperture 38 in the upper part of the gear 36 is adapted to receive 110 the cylindrical lower extremity 39 of the upper portion 20^a of the brake mast. The

part 39 rotates in the bearing 38 and thus maintains the two portions of the brake mast in alinement. The gear 36 is provided on its underside with an annular groove 40, 5 forming a raceway for the ball-bearings 41 which travel upon the upper surface of the plate 14 and thus support the weight of the brake mast, it being apparent that the gear member 25 and the upper portion 20^a of the 10 brake mast are adapted to rest upon and be supported by the gear 36.

The lower portion 20^b of the brake mast extends downwardly below the end sill of the car, and the lower reduced extremity 43 15 thereof is journaled in the horizontal portion of the step 44 which is carried by the end sill. The lower portion of the brake mast is provided with an aperture 45 adapted to be engaged by a bolt or the like for 20 securing the brake mast to the chain or other device by which the brakes are operated.

In the operation of the invention, the rotation of the upper portion of the brake mast operates to drive the pinion 29, which 25 in turn drives the relatively large gear 30 formed integrally with the pinion 35. The relatively small pinion 35 drives the large gear 36, and thus the lower portion of the brake shaft is rotated at a lesser speed than 30 the upper part, although the force applied by the lower portion 20^b is multiplied. After the brakes have been set in the desired position, the pawl 28 may be thrown into the proper position to engage the ratchet wheel 35 26, and thereby prevent rotation of either the upper or lower part of the brake mast. The simple construction of the driving gears and the formation of adjacent gears as integral members make it possible to provide 40 a compact transmitting mechanism which occupies a minimum amount of space adjacent the end sill of the car.

Although I have shown and described one embodiment of the invention for purposes 45 of illustration, it will be understood that it may be constructed in various other forms without departing from the scope of the appended claims.

What I claim is:

50 1. The combination in railway brake mechanism, of a brake mast formed in alining sections, gears mounted on the adjacent ends of said sections, an integrally formed gear member mounted on one side of said 55 first-named gears and meshing therewith, a ratchet wheel formed integrally with one of said gears, and a pawl adapted to engage said ratchet wheel.

2. The combination in railway brake 60 mechanism, of a brake mast formed in alining sections, gears mounted on the adjacent ends of said sections, an integrally formed gear member mounted at one side of said first-named gears and meshing therewith, a 65 ratchet wheel formed integrally with one of

said gears, a pawl adapted to engage said ratchet wheel, and a housing adapted to inclose said ratchet wheel and all of said gears.

3. The combination in railway brake mechanism, of a vertical brake mast formed 70 in alining sections, a plurality of gears connecting said sections, one of said gears being provided with an annular raceway, a supporting plate, and ball-bearings mounted in said raceway and adapted to travel on said 75 plate.

4. The combination in railway brake mechanism, of a vertical brake mast formed in alining sections, gears mounted on the adjacent ends of said sections, other gears operatively connecting said first-named gears, 80 the lower one of said first-named gears being provided with an annular raceway, a supporting plate mounted beneath said gears, and ball-bearings mounted in said 85 raceway to travel on said plate.

5. The combination in railway brake mechanism, of a vertical brake mast formed in alining sections, a gear secured to the upper end of the lower section, gearing mechanism for connecting said gear with the upper section of said brake mast, said upper section and a portion of said gear mechanism being supported by said gear, said gear being provided with an annular raceway on its 90 underside, a supporting plate having an aperture therethrough to receive the lower section of said mast, and ball-bearings mounted in said raceway and adapted to travel on said plate. 100

6. The combination in railway brake mechanism, of a vertical brake mast formed in two alining sections, a horizontal supporting plate, a housing mounted on said plate, a pair of gears connected to the ends 105 of said shaft within said housing, and a pair of integrally formed gears mounted in said housing and meshing with said first-named gears.

7. The combination in railway brake 110 mechanism, of a vertical brake mast formed in two alining sections, a horizontal supporting plate, a housing mounted on said plate, a gear mounted to the lower section of said mast within said housing, said gear having a part forming a bearing for the lower extremity of the upper section of said mast, a second gear mounted upon said upper section above said first-named gear, and a pair of connecting gears mounted in said 115 housing and meshing with said first and second named gears. 120

8. The combination in railway brake mechanism, of a vertical brake mast formed in two alining sections, a horizontal supporting plate, a housing mounted on said plate, a pair of gears mounted on the abutting ends of said sections within said housing, a ratchet wheel formed integrally with the upper gear, a driven gear mounted in 125 130

- said housing and meshing with said upper gear, and a pinion formed integrally with said driven gear and meshing with the lower one of said first-named gears.
- 5 9. The combination in railway brake mechanism, of a vertical brake mast formed in two alining sections, a horizontal supporting plate, a housing mounted in said plate, a pair of gears mounted on the abutting ends of said sections, said housing hav-
- 10 ing a lateral extension, an integrally formed gear member located in said lateral extension and having teeth meshing with both of said first-named gears, a vertically removable bearing pin for said gear member, and means 15 for securing said bearing pin in position.
- In testimony whereof, I have subscribed my name.

EDWARD POSSON.
